UNITED STATES PATENT OFFICE.

JOSHUA W. JONES, OF HARRISBURG, PENNSYLVANIA.

BALE-TIE.

SPECIFICATION forming part of Letters Patent No. 247,197, dated September 20, 1881.

Application filed January 22, 1881. (No model.)

To all whom it may concern:

Be it known that I, JOSHUA W. JONES, of the city of Harrisburg and State of Pennsylvania, have invented a new and useful Bale-Tie, of which the following is a specification.

My invention relates to improvements in bale-ties in which the tie is preserved for repeated use; and the objects of my improvement are, first, to provide a chain with a peculiar bed-piece as the connector, by which one end of said chain is permanently fastened thereto and the other end is caught in a peculiar jaw or cleft on the opposite end of said bed-piece; second, a peculiar conformation of said jaw or cleft to the part of the chain embedded therein, and a novel flaring depression in said bed-piece, whereat, by the use of a pry or lever, the caught link is easily released by a cant from said pry. I attain these objects by mechanism illustrated in the accompanying drawings, in which—

Figure 1 is an end view of my entire device applied to a bale of sheets of paper pressed between boards. Fig. 2 represents a front view of my locking bed-piece, to which both ends of the chain are shown to be applied, and an unlocking-lever is also shown inserted in one of the links. Fig. 3 represents the bed-piece.

Similar letters refer to similar parts throughout the several views.

The common links A', the long link C, and the bed-piece B represent my improved bale-tie.

The long link C is added for cheapness, as well as for convenience in applying the chain to a bale; but it may be omitted.

The end F of the chain A is connected by a stub-rivet, N, in the cleft end of the bed-piece B. The other end of said chain has any one of its links A' caught between and on the abutments M M, located on said bed-piece B, as shown. The adjacent links to the one caught are allowed to retreat into the depressions K L in said piece B. Said abutments are squarely

terminated behind and pitched toward each other, to form a seat for the caught link A', while the adjacent link, A², is entered on edge between said abutments in a peculiarly-rounded crevice or depression, K.

Beneath the link A' is the depression L, of semi-oval form, as shown, so made that when said link A' is drawn against or into the jaw of the abutments M the opposite end of the said link may be canted and wrenched by any suitable tool, as a pry, Q, to release it of its hold on or stress against said abutments when the bale is to be opened. More particularly, the caught end of the link A' is made to climb over the abutments M M, while the opposite end of said link is pressed by any suitable tool into the depression L, thus enabling the caught link to jump said abutments.

My improvement is applicable for tying under pressure papers, books, hay, cotton, and other matters, and the tie can be repeatedly used.

Having fully and clearly described my invention, what I regard as new and useful, and what I desire to secure by Letters Patent of the United States, is—

1. The bale-tie composed, essentially, of chain A and the bed-piece B M, attached thereto, they being constructed and applied substantially as set forth.

2. The bed-piece B M, provided with depression L, caught link A', and pry Q, all operating conjointly to produce the bale-tie release, substantially as set forth.

In testimony that I claim the foregoing as my invention I have hereunto set my hand and seal, this 20th day of January, 1881, in presence of two witnesses.

JOSHUA W. JONES. [L. S.]
